Primary Examiner — Karen S Acker*Assistant Examiner* — Wendy Arminio(74) *Attorney, Agent, or Firm* — Banner & Witcoff, Ltd.(57) **CLAIM**

The ornamental design for a dispenser head, as shown and described.

DESCRIPTION

FIG. 1 is a top, front, left perspective view of a dispenser head showing our new design;

FIG. 2 is a top, rear and right perspective view thereof;

FIG. 3 is a front view thereof;

FIG. 4 is a rear view thereof;

FIG. 5 is a left side view thereof; wherein the right side view

is a mirror image of FIG. 5; and,

FIG. 6 is a top view thereof.
